UNITED STATES PATENT OFFICE.

MAURICE J. KARPELES, OF PROVIDENCE, RHODE ISLAND.

DESIGN FOR A DISPLAY-CABINET.

47,957.

Specification for Design.

Patented Oct. 12, 1915.

Application filed July 23, 1915. Serial No. 41,607. Term of patent 7 years.

To all whom it may concern:

Be it known that I, MAURICE J. KARPELES, a citizen of the United States, residing at Providence, in the county of Providence and State of Rhode Island, have invented a new, original, and ornamental Design for Display-Cabinets, of which the following is a specification, reference being had to the accompanying drawing, forming part thereof.

The figure is a perspective view of a display cabinet showing my new design.

I claim:—

The ornamental design for a display cabinet, as shown.

MAURICE J. KARPELES.

Witnesses:

LULU R. KEENE,
LAURA B. ASHWORTH.
